UNITED STATES PATENT OFFICE

2,431,845

PYRETHRIN SYNERGIST

Martin E. Synerholm, Hastings on Hudson, N. Y.,
assignor to Boyce Thompson Institute for Plant
Research, Inc., a corporation of New York

No Drawing. Application August 3, 1944,
Serial No. 547,983

3 Claims. (Cl. 167—24)

1

This invention relates to insecticides for combating insect pests, such as flies, moths, mosquitoes and the like, and has for its object the provision of an improved insecticidal composition.

I have found that compounds having the formulae

I

II

where R is represented by a radical of the group consisting of propyl, butyl, cyclohexyl, benzyl, and allyl are exceptional synergistic agents in compositions comprising a pyrethrin in a spray medium, advantageously a mutual solvent. Spray compositions comprising one or more of the compounds and pyrethrin in a hydrocarbon or mineral oil, such as odorless kerosene or naphtha are especially effective insecticides and exhibit strong synergistic phenomena.

The tetrahydronaphthalene derivatives represented by Formula I may be prepared by heating together isosafrole and esters of maleic acid containing the appropriate R group. The use of chloromaleic esters leads to compounds presumably of Formula II.

The aforementioned compounds increase the toxic effect of pyrethrins to a very marked extent and when they are incorporated in a suitable spraying medium with pyrethrin or like extracts the resulting composition has more killing effect against such insects as the ordinary housefly than the combined effects of the pyrethrin and the compound when used alone. The invention provides an improved insecticidal composition comprising one or more compounds of the group consisting of

I

II

where R is a radical of the group consisting of propyl, butyl, cyclohexyl, benzyl, and allyl, and pyrethrin in a liquid spray medium, for example, of hydrocarbon character, such as odorless kerosene or naphtha.

The compounds used in the composition of the

invention may be formed by condensation of isosafrole and the propyl, butyl, cyclohexyl, benzyl, or allyl esters of maleic acid, chloromaleic acid, or substitution products thereof, and R in the formulae represents groups, the nature of which depends upon the particular maleic ester used. The synergistic effect of the compounds is shown in the following table in which the results were obtained by the Standard Peet-Grady method with five-day old flies as described on pages 92 to 98 of "Pyrethrum Flowers" by C. B. Gnadinger, 1936 edition, with compositions comprising compounds represented by the formula

and 0.025 gm. pyrethrin per 100 ml. of odorless kerosene:

	R	Grams per 100 ml.	Per Cent Kill	OTI Per Cent Kill	Adj. Per Cent Kill
25	n-Propyl	1.0	99	46	99
	0.5	93	46	94	
	0.25	76	46	78	
	0.5	87	48	88	
30	n-Butyl	0.25	75	51	74
	0.125	49	51	48	
	0.5	25	76		
	Cyclohexyl	2.0	95	58	94
35	Benzyl	1.0	92	56	86
	1.0	94	71		
	0.5	91	71		
	0.25	82	71		
	Benzyl (no pyrethrin)	1.0	42	71	

The following are the results of tests using 0.025 gm. pyrethrin per 100 ml. of odorless kerosene and the compound identified by the formula:

I claim:

1. An insecticidal composition comprising py-

rethrin and a compound represented by the formulae of the group consisting of

where R is a radical of the group consisting of 10 propyl, butyl, cyclohexyl, benzyl, and allyl.

2. An insecticidal composition according to claim 1 in which the compound and pyrethrin are dissolved in kerosene.

3. An insecticidal composition according to claim 1 in which the compound and pyrethrin are dissolved in a hydrocarbon solvent.

MARTIN E. SYNERHOLM.
